UNITED STATES PATENT OFFICE.

JOSEPH KIDD, OF DULUTH, MINNESOTA.

SHIP CONSTRUCTION.

No. 818,259.

Specification of Letters Patent.

Patented April 17, 1906.

Application filed May 18, 1905. Serial No. 260,255.

To all whom it may concern:

Be it known that I, JOSEPH KIDD, a resident of Duluth, in the county of St. Louis and State of Minnesota, have invented certain new 5 and useful Improvements in Ship Construction; and I do hereby declare the following to be a full, clear, and exact description of the invention, such as will enable others skilled in the art to which it appertains to make and 10 use the same.

My invention relates to an improved ship construction, the object of the invention being to provide an improved double-hull ship forming a series of water-tight compartments 15 and the upper or inner hull provided on its bottom with approximately inverted-V-shaped peaks or partitions running across the hull, forming a permanent part of the ship construction, greatly strengthening the ship's 20 bottom, constituting parts of the water-compartments to increase the capacity for water ballast in the compartments, and also forming a series of hoppers to direct the cargo beneath the hatches for ready removal by the 25 ordinary excavating-buckets.

With these and other objects in view the invention consists in certain novel features of construction and combinations and arrangements of parts, as will be more fully hereinabove 30 described, and pointed out in the claims.

In the accompanying drawings, Figure 1 is a fragmentary view, in longitudinal section, illustrating my improvements; and Fig. 2 is a similar view in cross-section.

35 1 represents the outer hull of the ship, and 2 an inner hull spaced therefrom and having suitable bars and braces, as shown, to strengthen the construction. The outer and inner hulls 1 and 2 form a chamber between 40 them divided off by suitable bulkheads or partitions 4 into a number of water-tight compartments which can be readily filled with water for ballast. As many bulkheads may be provided as desired, separating the 45 water-chamber into separate compartments, and the hulls are provided with cross and longitudinal braces to give the necessary strength thereto.

Extending across the ship and forming 50 fixed portions of the inner hull are a number of approximately inverted-V-shaped partitions 3, extending up from the bottom of the inner hull the desired distance. These hollow partitions 3 communicate with the water-compartments and in addition form a series of hoppers extending across the ship lo-

cated beneath the hatches and into which the bulk cargo feeds by gravity and can be readily removed therefrom by the excavating-buckets.

60 It will be observed that the partitions 3 have in cross-section a general inverted-V shape. The sides near the bottom are perpendicular to the hull 2 and then incline toward each other to a converging point. The 65 perpendicular portions of the partitions are of any desired height, yet preferably about one-half the height of the partitions, and such shape prevents the cargo sticking and compels its downward feed, and the partitions 70 also prevent possibility of the vessel sagging by reason of an unequal distribution of the load. The bottom is so strengthened by the partitions that all the cargo might be piled in the middle of the hold without causing the 75 vessel to sag. The partitions are built in and solidly riveted to the hull and form a permanent rigid portion thereof and also serve to permit the water ballast to come up high, increases the capacity, and renders the vessel 80 more seaworthy.

Various slight changes might be made in the general form and arrangement of the parts described without departing from my invention, and hence I do not restrict myself 85 to the precise details set forth, but consider myself at liberty to make such slight changes and alterations as fairly fall within the spirit and scope of my invention.

Having fully described my invention, what 90 I claim as new, and desire to secure by Letters Patent, is—

1. The combination of an inner and outer hull forming water-compartments between them and lateral hollow partitions on the 95 bottom of the inner hull communicating with the water-compartments and forming a series of lateral hoppers for the bulk cargo.

2. In a ship, the combination with an outer hull, of an inner hull spaced therefrom and forming water-compartments, hollow partitions on the bottom of the inner hull communicating with and forming part of the water-compartments, and said partitions so shaped as to form a series of hoppers across the ship 100 down into which the bulk cargo will feed by gravity.

3. In a ship, the combination with an outer hull, of an inner hull spaced therefrom and forming a water-space between them, bulkheads dividing said space into water-compartments, hollow partitions of approximately 105

inverted-V shape in cross-section, extending across the ship, built into the bottom of the inner hull, communicating with the water compartments and constituting a part there-
5 of, and forming a series of lateral hoppers into which the bulk cargo feeds by gravity.

4. In a ship, the combination with an outer hull, of an inner hull spaced therefrom, and forming a water-space between the hulls, the
10 bottom of the inner hull so shaped as to form a series of hoppers across the ship beneath.

the hatches, and means dividing said space into a number of separate water-tight compartments.

In testimony whereof I have signed this 15 specification in the presence of two subscribing witnesses.

JOSEPH KIDD.
